[57] ABSTRACT

A horizontally elongated support frame including a single center mounting point at one end and a pair of opposite side mounting points at the other end by which the frame may be supported from a plurality of makes of refrigerators and/or freezers, the frame itself including further mounting means adapted to support a plurality of motor/compressor and condenser assemblies of different makes therefrom whereby the frame may be utilized to support specific motor/compressor and condenser assemblies from various refrigerators and/or freezers, not necessarily of the same manufacturer.

The bracket of the instant invention comprises a frame for mounting beneath a refrigerator or freezer and includes structure by which the step of mounting the frame from the refrigerator or freezer may be readily carried out with little effort on many different refrigerators and freezers of different manufacturers. Also, each of the three forms of support frame specifically disclosed hereinafter include structure by which motor/compressor and condenser assemblies of various manufacturers may be supported therefrom.

REPLACEMENT REFRIGERATOR COMPRESSOR BRACKET

There are many instances when repair of refrigerators and freezers requires the replacement of the motor/compressor and condenser assemblies thereof. Additionally, the motor/compressor and condenser assemblies of different manufacturers render different quality service with the result that certain motor/compressor and condenser assemblies of a particular manufacturer may be considered as a preferred replacement assembly for a malfunctioning motor/compressor and condenser assembly of a refrigerator or freezer of a different manufacturer. In such an instance, inasmuch as mounting of the preferred motor/compressor and condenser assembly in the refrigerator or freezer being repaired involves considerable adaptations in view of the replacement assemblies being the product of one manufacturer and the refrigerator or freezer being the product of another manufacturer, the preferred replacement assemblies are not used.

It is accordingly the main object of this invention to provide a motor/compressor and condenser mounting frame adapted to support the motor/compressor and condenser assemblies of various manufacturers therefrom and further adapted for ready installation in freezers and refrigerators of different manufacturers.

Another object of this invention, in accordance with the immediately preceding object, is to provide a replacement refrigerator and freezer motor/compressor and condenser bracket constructed in a manner enabling the motor/compressor and condenser assemblies of various manufacturers to be quickly mounted thereon.

A final object of this invention to be specifically enumerated herein is to provide a mounting bracket or frame in accordance with the preceding which will conform to conventional forms of manufacture, be of simple construction and easy to use so as to provide a device that will be economically feasible, long lasting and relatively trouble free.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIG. 1 is a bottom plan view of a refrigerator with a first form of the bracket of the instant invention illustrated supporting the combined motor and compressor assembly as well as the condenser assembly of a refrigeration unit therefrom and thus within the lower portion of the refrigerator;

FIG. 2 is a perspective view of a second form of support bracket;

FIG. 3 is an enlarged fragmentary sectional view illustrating the manner in which one of the side mounting portions of the first modified form of mounting bracket may be supported from an adjacent portion of the associated refrigerator or freezer;

FIG. 4 is a fragmentary enlarged sectional view illustrating the manner in which the single end mounting portion of the first modified form of mounting bracket may be supported from an adjacent portion of a refrigerator or freezer;

FIG. 5 is a plan view of a second modified form of mounting bracket;

FIG. 6 is a fragmentary sectional view taken substantially upon the plane indicated by the section line 6-6 of FIG. 5;

FIG. 7 is a transverse vertical sectional view taken substantially upon the plane indicated by the section line 7-7 of FIG. 5;

FIG. 8 is a fragmentary vertical sectional view taken substantially upon the plane indicated by the section line 8-8 of FIG. 5; and

FIG. 9 is a perspective view of the slidable cross member of the second modified form of mounting bracket illustrated in FIG. 5.

Referring now more specifically to the drawings the numeral 10 generally designates a conventional form of refrigerator. The lower end portion of the refrigerator 10 includes opposite side inturned mounting flanges 12 and 14 and the area 16 between the flanges 12 and 14 and above a horizontal plane in which the flanges 12 and 14 are contained defines a space in which refrigeration components such as motor/compressor and condenser assemblies may be supported.

The mounting bracket of the instant invention is referred to in general by the reference numeral 18 and comprises an elongated frame including first and second ends 20 and 22. The frame 18 is defined by a generally U-shaped member 24 including opposite side legs 26 and 28 interconnected at one pair of corresponding ends by means of an integral bight portion 30. The U-shaped member opens toward the second end of the frame and a transverse member 32 is secured to and extends between and beyond the free ends of the legs 26 and 28. Further, a second transverse member 34 is secured to and extends between the legs 26 and 28 a spaced distance toward the bight portion 30 from the transverse member 32.

A pair of socket defining brackets 36 are secured to the mounting flange 14 by means of suitable fasteners 38 and the brackets 36 define cylindrical sockets in which the opposite ends of the transverse member 32 are received and secured by means of set screws 40 carried by the socket defining brackets. Further, a generally channel-shaped elongated center slotted bracket 42 is secured to and projects outwardly from the bight portion 30 and a second channel member 44 is telescoped within the outer end of the bracket 42 and secured thereto by means of a fastener 46 secured through the slot in the bracket 42 and a suitable bore provided therefor in the adjacent end of the channel member 40. In addition, the outer free end of the channel member 44 is slotted as at 48 and is secured to the mounting flange 12 by means of a suitable fastener 50 secured to the flange 12 and the slot 48 in the channel member 44. Accordingly, the bracket 42 and channel member 44 may be adjusted relative to each other and the fastener 50 may be adjusted longitudinally of the channel member 44 so as to compensate for varying distances between mounting flanges of refrigerators corresponding to the mounting flanges 12 and 14. In this manner, the frame 18 may be adjusted in effective length so as to be readily adapted for support from the lower end of different types of refrigerators and freezers.

60

65

Further, the socket defining bracket 36 may be secured in adjusted position along the corresponding ends of the transverse member 32 and secured in adjusted position by means of the set screws 40 so as to vary the spacing between the socket defining brackets 36 according to the spacing between the apertures provided on the associated refrigerator to receive the fasteners 38.

By the foregoing, it may be seen that the frame 18 can be readily secured to the refrigerators and freezers of various manufacturers.

The ends of the legs 26 and 28 adjacent the bight portion 20 are provided with longitudinally spaced apertures 52 through which suitable clamp fasteners may be secured to mount a condenser assembly such as the assembly 54 on the frame 18. In addition, a combined motor and compressor assembly 56 may be supported from the transverse members 32 and 34 by means of suitable fasteners 58. Therefore, motor/compressor and condenser assemblies of various manufacturers may be readily supported from freezers and refrigerators of different manufacturers by utilizing the frame 18.

With attention now invited more specifically to FIGS. 2 through 4 of the drawings, there will be seen a second form of mounting bracket or frame referred in general by the reference numeral 18' and whose components are similar to the various components of the frame 18 and are therefore designated by corresponding prime reference numerals. The frame 18' differs from the frame 18 in that a mounting plate 53 is secured over the upper surface of the portion of the frame 18 bounded by the transverse members 34' and 32' and the adjacent ends of the legs 26' and 28'. Otherwise, the frame 18' is substantially identical to the frame 18.

With reference now more specifically to FIGS. 5 through 9 of the drawings it will be seen a third form of mounting bracket whose components corresponding to the various components of the mounting bracket 18 are referred to by corresponding reference numerals in the 100 series. The mounting bracket 118 differs from the mounting bracket 18 in that the bight portion 120 thereof includes an outwardly projecting tubular neck 121 in whose outer end one end of a tubular member 123 is telescoped, a compression spring 125 being seated in the neck 121 and engaged with the adjacent end of the tubular member 123. The end of the tubular member 123 remote from the compression spring 125 is flattened as at 127 and has an aperture 129 formed therein by which the end of the tubular member 123 may be secured to a mounting flange such as the 55 mounting flange 12.

In addition, the transverse member 122 has two pairs of apertures 158 formed therein and the transverse member 134 has two pairs of apertures 158 formed therein. Further, with attention also invited to FIG. 9 of the drawings, it may be seen that the transverse member 134 comprises a tubular member whose opposite ends have semicircular recesses 135 formed therein which guidingly engage the confronting side surfaces of the legs 126 and 128. Accordingly, the transverse member 134 may be adjusted toward and away from the transverse member 122.

The legs 126 and 128 each have three apertures 152 formed therein and accordingly, any given set of the apertures 152 may be utilized in securing a corresponding condenser assembly such as the assembly 154 to the frame 118. Also, any set of the apertures 158 may be utilized together with shifting of the transverse member 134 relative to the transverse member 122 in order to adapt the end of the frame 118 remote from the neck 120 to have a combined motor and compressor assembly of substantially any manufacturer secured thereto. Still further, the socket defining brackets 136 of the frame 118 are somewhat longer than the socket defining brackets 36 and each includes a pair of set screws 140 for releasable securing of the brackets 136 to the opposite ends of the transverse member 122 in adjusted position therealong. Therefore, it may be seen that the mounting bracket or frame 118 may be readily adjusted not only so that it will be adapted for 10 secured to a refrigerator or freezer of a particular manufacturer but also to enable the motor/compressor and condenser assemblies of a particular manufacturer to be secured thereto.

The foregoing is considered as illustrative only of the 15 principles of the invention. Further, since numerous modifications and changes will readily occur to those skilled in the art, it is not desired to limit the invention to the exact construction and operation shown and described, and accordingly all suitable modifications 20 and equivalents may be resorted to, falling within the scope of the invention.

What is claimed as new is as follows:

1. An elongated mounting bracket having first 25 mounting means at one end and intermediate the sides thereof adjustably extendible lengthwise of said bracket outwardly of said one end and second opposite side mounting means at the other end thereof adjustably extendible transversely of said bracket outwardly of the corresponding sides of said bracket, said mounting bracket including means intermediate its ends adapted to support motor, compressor and condenser assemblies therefrom.

2. The combination of claim 1 wherein said endwise 30 extendible mounting means at said one end of said bracket includes an endwise outwardly projecting slotted channel-shaped member secured to said one end of said bracket, a second channel member telescoped within the outer end of the first mentioned 35 channel member and secured to the latter by means of a fastener extending through the slotted portion of the first mentioned channel member, the outer end of the second mentioned channel member being adapted for 40 secured to a support portion.

3. An elongated mounting bracket having first 45 mounting means at one end and intermediate the sides thereof adjustably extendible lengthwise of said bracket outwardly of said one end and second opposite side mounting means at the other end thereof adjustably extendible transversely of said bracket outwardly of the corresponding sides of said bracket, said mounting bracket including means intermediate its ends adapted to support motor, compressor and condenser assemblies therefrom, said first extendible 50 mounting means at one end of said bracket including a tubular neck projecting endwise outwardly from and being secured to said one end of said mounting bracket,

a tubular member telescoped in the outer end of said tubular neck, the outer end of said tubular member being adapted for securement to a support portion.

4. The combination of claim 3 including a compression spring seated in said tubular neck and bearing against the adjacent end of said tubular member telescoped within the outer end of said neck.

5. An elongated mounting bracket having first mounting means at one end and intermediate the sides thereof adjustably extendible lengthwise of said bracket outwardly of said one end and second opposite side mounting means at the other end thereof adjustably extendible transversely of said bracket outwardly of the corresponding sides of said bracket, said mounting bracket including means intermediate its ends adapted to support motor, compressor and condenser assemblies therefrom, said outwardly extendible opposite side mounting means at the other end of said bracket including elongated endwise outwardly projecting mounting portions carried by opposite sides of said other end of said bracket and elongated tubular elements telescoped over the outer ends of said mounting portions and releasably secured in adjusted position therealong, the remote ends of said tubular elements including means adapted for support from suitable mounting portions.

6. The combination of claim 5 wherein said endwise extendible mounting means at said one end of said bracket includes an endwise outwardly projecting slotted channel-shaped member secured to said one end of said bracket, a second channel member telescoped within the outer end of the first mentioned channel member and secured to the latter by means of a fastener extending through the slotted portion of the

first mentioned channel member, the outer end of the second mentioned channel member being adapted for securement to a support portion.

7. The combination of claim 5 wherein said endwise extendible mounting means at one end of said bracket includes a tubular neck projecting endwise outwardly from and is secured to said one end of said mounting bracket, a tubular member telescoped in the outer end of said tubular neck, the outer end of said tubular member being adapted for securement to a support portion.

8. The combination of claim 1 wherein said means intermediate the opposite ends of said mounting bracket includes spaced bores formed in the opposite sides of said mounting bracket.

9. The combination of claim 1 wherein said means intermediate the opposite ends of said mounting bracket includes a transverse member extending between the opposite sides of said mounting bracket intermediate the opposite ends thereof and having spaced apertures formed therein.

10. The combination of claim 9 wherein said transverse member is supported from said bracket for adjustable shifting longitudinally of said bracket.

11. The combination of claim 10 wherein said mounting bracket includes a second transverse member extending between the opposite sides of said other end of said bracket and relative to which the first mentioned transverse member is shiftable, said first mentioned transverse member being freely shiftable relative to the second mentioned transverse member, the second mentioned transverse member also including apertures formed therethrough at points spaced longitudinally therealong.
